UNITED STATES PATENT OFFICE.

THOMAS LEGGETT STURTEVANT, OF QUINCY, AND THOMAS JOSEPH STURTEVANT, OF WELLESLEY, MASSACHUSETTS, ASSIGNEES TO STURTEVANT MILL COMPANY, A CORPORATION OF MAINE.

CRUSHER.

1,013,459.

Specification of Letters Patent.

Patented Jan. 2, 1912.

Application filed October 27, 1908. Serial No. 459,691.

To all whom it may concern:

Be it known that we, THOMAS L. STURTEVANT and THOMAS J. STURTEVANT, citizens of the United States, residing, respectively, 5 at Quincy and Wellesley, in the county of Norfolk and State of Massachusetts, have invented or discovered certain new and useful Improvements in Crushers, of which the following is a specification, reference 10 being had therein to the accompanying drawings.

This invention relates to that class of 15 rocking jaw crushers in which the side plates are of steel and are comparatively thin or light, with a view to easy transportation in mountainous countries or over rough roads; and the invention has for its object to provide a crusher of this class which may be constructed at a minimum 20 cost, but which will be durable and efficient in operation. In this class of crushers in which the frames comprise relatively thin plates more or less difficulty has been experienced in providing suitable bearings at 25 the rear portions of the frames for the driving shafts carrying the cams or eccentrics for operating the crushing jaws, as the strains and shocks are so great on these shafts that their bearings, when not sufficiently braced, are likely to be thrown out 30 of alinement, so that the machine will soon wear out or be comparatively short-lived for efficient operation. In our Patent No. 859,348, of July 9, 1907, we show and de- 35 scribe a construction intended to obviate this difficulty, and while the construction of said patent has proved to be efficient it has been found to be expensive to manufacture, and the present invention, which is an im- 40 provement on the construction of our said patent, is much cheaper to make than the construction of our said patent, and is equally efficient in operation.

In the present improved construction we 45 provide at the rear of the crusher a somewhat massive angle cross-beam, and we also provide somewhat heavy bearing-blocks for the driving shaft which are bolted to the said angle cross-beam and to the side plates 50 of the frame. This rigid cross-beam not only stiffens the frame of the crusher but also insures great rigidity of the bearing-blocks for the driving shaft, so that these bearing-blocks, in coöperation with the 55 heavy angle cross-beam, to which they are

rigidly bolted, as also to the side plates of the frame, secures a frame of great rigidity, and at the same time one which is relatively light as compared with the heavy cast metal frames of some rocking jaw crushers of this 60 class.

In the accompanying drawings, Figure 1 is a perspective view of our improved crusher, with one of the fly wheels removed. Fig. 2 is a side view of the same with one of 65 the side plates removed, and one of the fly wheels omitted, and Fig. 3 is a cross section on line 3—3, Fig. 2.

Referring to the drawings, 12 denotes the side plates of the crusher frame and which, 70 for lightness and strength, are preferably of steel, said frame also comprising a head block 13 at the front end of the frame, and an angle cross-beam 14 at the rear end of said frame, said parts being secured together, by a considerable number of through-bolts. Rigidly bolted to the angle cross-beam and to the side plates are bearing-blocks 15 having flanged portions registering with said angle cross beam, and in which 80 bearing blocks is mounted the driving shaft 16 provided, in the present instance, with a double cam 17. Running in contact with the said cam is a roller 18 carried by a swing- 85 ing lever 19 which operates the rocking jaw 20 through the medium of the interposed toggle-plate 21. Said rocking jaw 20 carries the moving crushing plate 22 coöperating with the stationary crushing plate 23 fixed to the head block 13. The roller 18 90 is held in contact with the cam 17 by means of a pull-back spring 24 encircling a rod 25 connected with the lower or free end of the rocking jaw 20 and engaging an abutment projection 26 formed integral with the angle 95 cross-beam 14; the stress of said spring being properly regulated by means of a nut 27 on said rod 25. The bearing blocks 15 are provided with cap plates or portions 28 100 suitably bolted to said blocks.

With a crusher constructed as above described, with the bearing blocks for the driving shaft rigidly secured to the somewhat massive angle cross-beam 14 by an approximately vertical and horizontal series of 105 through-bolts 29, which pass through the flanged portions of said bearing blocks and also through the side plates 12 and the angle cross beam 14, the rear portion of the frame is so stiffened and the bearing blocks so 110

rigidly attached to the frame that the driving shaft will be able to sustain the great stress and shocks to which it is at times exposed, without any possibility of loosening its bearings; while at the same time the crusher may be constructed at less expense than the crusher of our said Patent No. 859,348, in which the bearings for the driving shaft were formed integral with the rear cross-beam. By forming the abutment projection 26 integral with the angle cross-beam 14 the rigidity of the lower arm of said cross-beam is augmented, as will be understood.

15 The bearing-blocks 15 have projections or sleeve-like portions 30 projecting inward through openings in the side plates 12, said projections shouldering against said side-plates at the walls of said openings, and affording somewhat extended bearings. Owing to the fact that the said bearing blocks are thus shouldered against the said side plate, which are interposed between said blocks and the angle cross-beam 14, they 25 serve, to a certain extent, to relieve the bolts 29 of a part of the crushing strains, so that this construction assists in preventing any changes of alignment of the shaft bearings.

Having thus described our invention we 30 claim and desire to secure by Letters Patent:

1. A crusher comprising in its frame construction side plates, a rear, angle cross-beam having vertical and horizontal arms or flanges extending upwardly and inwardly, 35 respectively, from the rear lower corner of the frame, and bearing-blocks having flanged portions registering with said angle cross-beam, the said bearing blocks being secured to said side plates and angle beam by a series of bolts passing through the said flanged portions of said blocks and also through said side plates and the vertical and horizontal arms or flanges of said angle cross-beam.

2. A crusher comprising in its frame construction side plates having openings, a rear, angle cross-beam having vertical and horizontal arms or flanges extending upwardly and inwardly, respectively, from the rear lower corner of the frame, and bearing-blocks having flanged portions registering with said angle cross-beam, the said bearing blocks being secured to said side plates and angle cross-beam by a series of bolts passing through the flanged portions of said bearing

blocks and also through said side plates and the vertical and horizontal arms or flanges of said angle cross-beam, said bearing-blocks having projections extending inward through said openings in said side-plates and shouldering against the walls of said openings.

3. In a crusher, the combination with side plates, a head block, and a rear, angle cross-beam comprising vertical and horizontal arms or flanges, and provided with an abutment projection, of bearing blocks having flanged portions registering with said angle cross-beam, bolts passing through the said flanged portions of said bearing blocks and also through the said side plates and rear angle cross-beam, and serving to secure these parts rigidly together, a driving shaft journaled in said bearing blocks and provided with a cam or eccentric, a rocking jaw operated from said cam or eccentric, a pull-back 75 spring engaging said abutment projection, and a pull-back rod connected with said rocking jaw and which is encircled by said spring.

4. In a crusher, the combination with side 80 plates, a head block, and a rear, angle cross-beam comprising vertical and horizontal arms or flanges and provided with an abutment projection, of bearing blocks having flanged portions registering with said angle 85 cross-beam, bolts passing through the said flanged portions of said bearing blocks and also through the said side plates and said angle cross-beam so as to secure said parts rigidly together, a driving shaft journaled 90 in said bearing blocks and provided with a cam or eccentric, a rocking jaw operated from said cam or eccentric, a pull-back spring engaging said abutment projection, and a pull-back rod connected with said 95 rocking jaw and which is encircled by said spring, said bearing-blocks having projections extending inward through openings in said side-plates and shouldering against the walls of said openings.

In testimony whereof we affix our signatures, in presence of two witnesses.

THOMAS LEGGETT STURTEVANT.
THOMAS JOSEPH STURTEVANT.
